FLUID LIFTING APPARATUS FOR WELLS

Lee O. Koen, Houston, Tex.

Application December 14, 1935, Serial No. 54,392

18 Claims. (Cl. 103—240)

This invention relates to new and useful improvements in fluid lifting apparatuses for wells.

One object of the invention is to provide an improved fluid lifting apparatus adapted to be installed in a well, and so arranged when operated, as to discharge intermittently, slugs or ascertained quantities of fluid, and thus flow the well; or to aerate the fluid column standing in the well, thereby assisting the well to flow intermittently, in heads, or constantly.

An important object of the invention is to provide a fluid lifting apparatus involving valve mechanism adapted to be installed in a well for shutting off and for admitting fluids and liquids, and means extending from the valve mechanism upwardly in the well controllable from the surface, for positively actuating the valve mechanism; such actuating means either being flexible and connected with a weight for holding it taut and producing operation when it is reciprocated, or being rigid but possessing sufficient inherent weight as to either require very little added weight or none at all.

Another object of the invention is to provide an improved fluid lifting apparatus including valve mechanism adapted to be installed in a well; and actuating means, so arranged as to be lowered from the surface, and engaged with the valve mechanism for operating the latter from the surface as desired; or released from the valve mechanism and withdrawn from the well, leaving the mechanism free from the operating means, so that tubing may be added or pulled from the well, without interference from, or injury to, the said operating means.

An object of the invention is to provide an improved fluid lifting apparatus including a liquid inlet valve and a pressure fluid inlet valve separated therefrom; and reciprocal means positively operable from the surface for individually actuating said valves.

Still another object of the invention is to provide an improved fluid lifting apparatus including a liquid inlet valve and a pressure fluid inlet valve; and flexible means extending up the well for reciprocation from the surface, and having operating connection with said valves, together with a weight for holding said connection taut to take up slack and stretch therein, whereby the length of the stroke may be reduced and a more positive and more sensitive operation of the valves, obtained.

Still another object of the invention is to provide a fluid lifting apparatus including a liquid inlet valve and a pressure fluid inlet valve, open-

ing to the tubing, and so arranged that the valves will be held closed while the apparatus is being installed, so that the tubing remains dry, but which may be released from the surface to free the valves.

An important object of the invention is to provide an improved fluid lifting device for use in a well so arranged that the timing of the opening and closing of the fluid and liquid inlet valves, may be positively controlled from the surface of the well, whereby the flowing of the well by means of a pressure fluid or with the aid thereof may be regulated to a maximum extent and comparatively accurate adjustments made from the surface of the duration of the lengths of the periods for which the valves are held open and/or closed.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a vertical sectional view of a portion of a well and the upper portion of an apparatus constructed in accordance with the invention, installed therein, the fluid pressure valves being closed.

Figure 2 is a similar view showing the lower portion of said apparatus, the liquid inlet valve being closed.

Figure 3 is a view similar to Figure 1 showing in full lines the fluid inlet valve closed and in dotted lines such valve opened.

Figure 4 is a view similar to Figure 2 showing the liquid inlet valve open.

Figure 5 is a view similar to Figure 1 showing the auxiliary fluid pressure inlet valve open.

Figure 6 is a view similar to Figure 4 showing the lower portion of the apparatus illustrated in Figure 5, the liquid inlet valves being open.

Figures 7 to 11, inclusive, are enlarged horizontal cross-sectional views taken on respective lines of Figures 1 and 2.

Figure 12 is an enlarged detail of the tripping mechanism for the fluid pressure valve.

Figure 13 is a similar view of the tripping mechanism for the liquid inlet valve.

Figure 14 is a view similar to Figure 1 showing another form of the invention.

Figure 15 is a view similar to Figure 2 and showing the lower portions of the parts illustrated in Figure 14.

Figure 16 is a detail of the spear releasing device, and

Figure 17 is a detail of the weight latch.

In the drawings, the numeral 20 indicates a tubular housing or hollow cylindrical casing, preferably of metal and made to contain fluids and liquids. This housing is adapted to be set in a casing 21 in any suitable manner, but preferably suspended from a string of tubing 22; also it is generally considerably less in diameter than the interior of the casing so as to leave a space therebetween. The lower end of the housing 20 is internally screw threaded to receive the screw threaded pin 23 (Figure 2) of a tubular packer sub 24, which carries a flexible packer 25 engaging the casing 21. A strainer 26 may be connected with the sub by a tubing 27.

The housing 20 is usually immersed in the liquid standing in the casing and the weight of the liquid above the packer will expand the same against the casing so as to form a fluid tight joint; any pressure fluid above the liquid will exert its pressure thereon and accentuate the expansion of the packer and overcome pressures below said packer. Any means may be employed to hold the housing in position in the casing, but usually the packer and the tubing will be sufficient.

Just above the pin 23 the housing has an internal flange 28 on which a lower head or valve block 29 rests. This head fits snugly in the housing and is tightly held upon said flange by a stem 30 which passes through a spider 31 engaging the underside of the flange. The stem is fastened in the spider by a nut 32. A plurality of uprights or stud bars 33 extend up the housing adjacent its inner wall, and as is best shown in Figures 7 to 11 inclusive, there are, preferably, three equally spaced bars, but the number may vary.

The bars support, at their upper ends, an upper head 34 which fits snugly in the upper end of the housing and has an upper screw threaded portion extending above the housing to receive a collar 35. A gasket 36 is interposed between the lower edge of the collar and the upper edge of the housing. The bars are welded or otherwise fastened in the heads 29 and 34 and these parts constitute a cage 37 which is immovably held in the housing by the stem 30 and spider 31, but which may be removed by disconnecting said stem and spider. When the collar 35 is screwed down upon the gasket, the bars 33 will be tensioned, whereby the cage will be given rigidity.

Intermediate the heads 29 and 34 a valve block 38 is disposed within the cage 37 and suitably fastened to one of the bars 33 as by welding. This block is formed with a right angular duct 39, the upper end of which is connected by a tubing 40 with a duct 41 extending through the head 34. An inlet tube 42 (Figure 1) extends from the upper end of the duct 41 upward through the collar into the casing to a point well above the maximum liquid level in said casing. A strainer 43 may be placed upon the upper end of the inlet tube so as to prevent any obstruction falling into the tube and clogging it or the parts connected therewith. This strainer 43 and tube admit air or gas under pressure which is conducted to the duct 39. It will be apparent that the housing 20 being closed at each end, fluid pressure can only enter through the strainer 43 and tube 42.

75 A vertical passage 44 extends through the block

38 and intersects the duct 39, as is best shown in Figure 5. Valve seats 45 and 46 are formed in the passage immediately above and below the duct 39 for receiving valve heads 47 and 48 which either open or close said passage to permit the pressure fluid to flow through the passage into the upper and lower portions of the housing. The valve heads are fastened together and a stem 49 depends from the lower head for raising and lowering said heads to open and close the passage. The valve head 48 exposes a greater area in the duct 39 than the head 47, and consequently the pressure fluid will tend to seat the valves. This seating action will be accentuated by a coil spring 50 surrounding the valve stem 49 between the block and a clevis 51 on the lower end of said stem.

For operating the valve heads a device is provided which is more clearly shown in Figure 12 and comprises a plunger 52 having its upper end pivoted in the clevis 51 and its lower portion telescoping a sleeve 53 which has a yoke 54 at its lower end straddling and pivoted to the medial portion of a tripping lever 55. The lever 55 has one end pivoted in a bracket 56 welded or otherwise fastened on the bar 33 which carries the block 38; while a roller 57 is journaled on the opposite or outer end of the lever. The sleeve 53 is provided with a transverse slot 58 and the plunger 52 carries a pin 59 extending through this slot and whereby the relative reciprocations of the plunger and sleeve are limited by the length of said slot.

A washer 60 surrounding the sleeve rests upon the pin 59 and engages the lower end of a coil spring 61 and has its upper end seated in a washer 62 fastened around the upper end of the sleeve 53. This spring is under compression so as to elevate the sleeve and hold the pin at the bottom of the slot 58, whereby the lever 55 is normally supported in a substantially horizontal position as is shown in Figure 1, the valves 47 and 48 being closed. It is obvious that any obstruction engaging the roller 57 and moving downwardly would swing the lever 55 downwardly which would pull the sleeve 53 downwardly whereby the pin 59 would slide in the slot 58 and compress the spring 61, as is shown in full lines in Figure 12. This would permit the downward passage of an obstruction without disturbing the valves 47 and 48. However, with the lever 55 in the position shown in Figure 1 an obstruction engaging the roller 57 would swing said lever upwardly to the position shown in dotted lines in Figures 3 and 12. This operation would raise the valves because the pin 59 resting on the bottom of the slot 58 would cause the plunger 52 to be lifted.

The lower head 29 is provided with right angular inlet ducts 63 and 64 which are reversed so that the duct 63 overhangs the duct 64 as is best shown in Figures 2, 4, and 6. The overhanging portions of the ducts communicate through a valve seat 65. A valve seat 66 in the top of the duct 63 communicates with a port 67 extending through the top of the block. A valve head 68 in the duct 64 engages the seat 66 and is fastened to a valve head 69 which engages the seat 65 in the duct 63. These heads are fastened to the lower end of a stem 70 extending from the port and having a clevis 71 on its upper end. A frusto-conical coil spring 72 surrounds the stem and has its lower end resting on the head around the port 67 and its upper end engaging the clevis. This spring is under compression so as to hold the

valves closed. When the valves are open, as is shown in Figure 4, fluid entering the duct 63 may flow through the valve seats and pass into the housing 20 through both the duct 64 and the port 67. As the valve head 69 exposes a greater area in the duct 63 than does the head 68, when the valves are closed, the liquid pressure will co-act with the spring to hold the valves closed.

It is desirable to alternately operate the fluid valve mechanism and the liquid valve mechanism and, therefore, mechanism is provided which operates oppositely to the lever 55. A lower lever 55' has a roller 57' and is pivoted in a bracket 56'. The valve operating mechanism attached to the lever 55 is simulated as is shown in detail in Figure 13. The upper end of the plunger 52' is pivoted to the lever and the lower end telescopes a sleeve 53' having a slot 58' receiving a pin 59'. It will be noted that the slot is in the upper end of the sleeve and normally the pin engages the upper end of the slot. A washer 60' rests upon a coil spring 61' surrounding the sleeve and supported on a washer 62' fastened on the lower end of the sleeve. A clevis 73 on the lower end of the sleeve is pivoted to the outer end of a counter lever 74 medially pivoted on a bracket 75 fastened on the bar 33 to which the other levers are attached. A link 76 has its upper end pivoted to the inner end of the lever 74 and its lower end pivoted in the clevis 71.

It is obvious that when an obstruction moving downwardly engages the roller 57', the lever 55' will be swung downwardly whereby the plunger 52' will be telescoped in the sleeve 53', thereby not depressing the sleeve or swinging the lever 74. The upward force exerted by the spring 72 aided by the liquid pressure against the valve head 69 will be sufficiently in excess of the compression of the spring 61' to hold the lever 74 against swinging. However, when an obstruction moving upwardly engages the roller 57' the pin 59' will lift the sleeve 53' and swing the lever 74, whereby the link 76 will be depressed and the liquid inlet valves 68 and 69, thus opened to admit liquid to the housing 20.

Any means which will positively operate the valve mechanisms or the valves themselves could be employed, so long as such means was arranged to be actuated from the surface and extended up the well. Such means would have to be sufficiently taut or under such tension as to operate within a pre-determined or ascertained length of stroke as to produce positive operation of the valves without losses due to stretch or slack, otherwise there would be too much lost motion and it would be difficult if not impossible to accurately time the opening and closing of the valves.

For actuating the levers 55 and 55', any suitable vertically movable means may be employed and satisfactory results have been obtained by the use of a vertical tripping bar 77 provided with tripping lugs 78 and 79. The lug 78 is located so as to engage the rollers 57 and 57' and operate the levers 55 and 55'; while the lug 79 is located to engage the roller 57' and actuate the lever 55'. These lugs have flat faces and sharply inclined ends so as to give a snap action when engaging the rollers, thereby producing quick opening and closing movements of the valves. It is desirable to prevent sand cutting to have these snap action operations. The tripping bar 77 is preferably connected to a positive operating medium extending up the well to the surface and this medium could be either a small rod or a wire line and

very satisfactory results have been obtained with the latter.

The upper end of the bar 77 is offset and fastened to the lower end of a socket 80 which is located directly under an opening 82 in the head 34, into the upper end of which opening the well tubing 22 is screwed. The socket 80 has a pair of spring pressed dogs 83 pivoted therein for receiving the head 84 of a spear 85. The spear is fastened on the lower end of a wire line 86 extending up the tubing. This wire line may be piano wire or any other flexible connection. The wire extends up the tubing to a suitable operating mechanism, not shown, which is located on the surface and arranged to reciprocate the wire. It would be possible to attach the spear 85 to the lower end of a chain, a cable, or a rod. Where a flexible connection is employed, it is necessary to keep the same taut and also to take up any slack or stretch so that when the line is reciprocated the bar 77 will be moved and will travel substantially the same length as the wire line is moved. For this purpose a suitable weight 87 may be attached to the lower end of the bar 77 or it could be attached at any other suitable point so long as it served the purpose set forth.

When the device is installed in the well, the housing 20 is attached to the lower end of the tubing 22 and immersed into the column of liquid standing in the casing 21. It is preferable to submerge the housing so that the liquid which enters the same will stand to a considerable depth in the tubing 22, the tubing 42 being long enough to extend above the liquid level. After the housing and tubing have been run into the well the spear 85 is lowered by the wire line. The socket has a flared guide 87 at its upper end so as to assure the head 84 entering said socket. The head is lowered into the socket, displacing the dogs 83 and catching thereunder as will be obvious. The wire line is then pulled upwardly until it is placed under tension and the slack and stretch taken out by slightly lifting the weight 87. When it is desired to release the wire line and withdraw the spear from the tubing a sleeve 45 weight 88 threaded on the wire line is permitted to run down the same and thence down the spear 85 until it strikes the dogs 83 and displaces them outwardly as is shown in Figure 16. The sleeve is larger in diameter than the head 84 and this permits the head to clear the dogs when the spear is withdrawn. The wire line and spear being removed from the well, the tubing 22 and housing 20 may be removed without interference therefrom.

When the apparatus has been properly installed in the well an upward pull is exerted on the wire line 86 to move the tripping bar 77 upwardly. This causes the upper end of the lug 78 (Figure 1) to engage the roller 57' and quickly swing the lever 55' which imparts a snap action. The roller rides on the surface of the lug during the continued upward movement. The swinging of the arm 55' rocks the lever 74 whereby the link 76 is forced downwardly, as shown in Figures 3 and 65 4, to open the valves 68 and 69. This admits liquid through the duct 63, duct 64 and port 67. The term "oil" will be used to designate the liquid and the term "gas" to designate the pressure fluid, but merely for the purpose of description 70 and explanation, as the invention is not to be limited thereto. The oil will rise filling the housing and flowing into the tubing to the point where it would stand in the casing.

The gas valves are closed and the oil valves will 75

remain open so long as the roller 57' rides on the face of the lug 78. When the end of the lug is reached the roller will abruptly drop therefrom, thus quickly closing the valves 68 and 69 and shutting off the admission of oil. Continued upward movement of the tripping bar 77 will cause the lug 78 to engage the roller 57 of the lever 55 and to abruptly swing the same upwardly, whereby the gas valves 47 and 48 will be opened. This will permit gas under pressure flowing by way of the conductors 43, 42, 41, 40 and 38 to enter the duct 44 and discharge from the block 38 into the housing 20. As the oil cannot be displaced downwardly the gas will act to displace the oil upwardly in the tubing 22. The time which the gas valves remain open is, of course, controlled by the length of the lug 78. As has been before explained the lug 78 may be moved downwardly and swing both levers 55 and 55' downwardly without actuating either the oil or the gas valves. The operation will be repeated on the next upward stroke and the rapidity of these strokes depends upon the flowing conditions of the well. This operation, of course, applies to intermittent actuation.

If a well shows a tendency to flow under its own pressure and it is desired to assist this natural flowing by introducing a pressure fluid into the column of oil, it would be necessary to hold the oil valve open for a longer period of time and this is accomplished by means of the second lug 79 which is located so as to engage the roller 57' when the tripping bar is raised to a higher position than for intermittent operation. When this occurs the first lug 78 which has passed from the roller 57 of the lever 55 engages the end of a lever 90 extending across the housing from a bracket 91 fastened on the bar 38 which carries the other lever. The block 38 is provided with a port 92 having a valve head 93 seated at its upper end and opening into the duct 39. The stem 94 of this valve extends down through the port and is attached to a clevis 95 pivoted on the lever 90. A coil spring 96 between the block and the clevis 95 holds the valve closed as is shown in Figure 1. When the lever is swung upwardly by the lug 78 the valve 93 will be opened thus admitting gas to the chamber 20. The port and valve 93 are smaller than the valves 47 and 48 because it will not be necessary to admit as great a quantity of gas to assist a flowing well. This gas which is admitted will aerate the column of oil thus increasing the flow. By permitting the tripping bar to remain stationary the oil and gas valves 55 may be held open as long as desired. The bar can also be adjusted to hold the valves closed when desired.

The mechanism which has been described provides for the opening of the oil and gas valves upon an upward pull of the wire line. It is apparent that this operation could be produced upon the downward travel of the tripping bar 77 and such an arrangement has been illustrated in Figures 14 and 15. Parts which are duplicated will be so numbered. It is obvious that the tripping mechanism in this form would have to be reversed. The stem 49 is shortened and the clevis 51 supports a washer 100 on which the lower end of a coil spring 101 is carried. This spring bears against the block 38 so as to hold the valves 47 and 48 closed. A link 102 has its upper end pivoted in the clevis while its lower end is pivoted to a counter lever 103 pivoted in a bracket 104 fastened on the bar 38. The mechanism 75 shown in Figure 13 is employed except that it is

reversed and by using the same reference numerals it is believed further explanation will be unnecessary except to say that the pin 78' will normally rest in the bottom of the slot 58'.

Consequently when the tripping bar 77 is moved upwardly and the lug 78 engages the roller 57 there will be no operation of the gas valves 47 and 48. However when the lug 78 is moved downwardly the lever 55 will be swung downwardly thereby opening the gas valves.

The stem 10 of the oil valves 68 and 69 is surrounded by a coil spring 105 which is confined between the head 28 and a washer 106 engaging under the clevis 71. A sleeve 107 has an ear 108 at its lower end pivoted in the clevis. This sleeve 15 receives the lower end of a plunger 109 carrying a pin 110 extending through a slot 111 much the same as the parts which have been described. A washer 112 resting on the pin supports a coil spring 113 having its upper end bearing against 20 a flange 114 on the upper end of the sleeve. The upper end of the plunger is pivoted to the medial portion of a lever 115 pivoted in a bracket 116 fastened on the bar 38 which carries the other levers. A roller 117 is journaled in the outer end 25 of the lever.

It is obvious that upon an upward movement of the lug 78 the lever 15 would be swung upwardly which would lift the plunger 109 and compress the spring 113 without effecting the valves 68 and 69. This compensating means operates substantially the same as those which have been described.

Upon a downward movement of the lug 78, the lever 115 would be swung downwardly and the plunger 109 moving downward would, through the agency of the pin 110, depress the sleeve 107 and thereby open the oil valves 68 and 69. All of the features which have been described in connection with the other form may be used in connection with this form.

In Figure 17, I have shown a latching device for suspending the weight 81, whereby the oil and gas valves are held closed when the housing 20 is being lowered into the well and until such time as it is desired to open them. In carrying out this feature the tripping bar 77 is provided with a slot 120 for receiving a hook latch 121. This latch is mounted to slide transversely of the housing in a yoke-shaped bracket 122 fastened on top of the valve block 38 so as not to interfere with the duct 44. A coil spring 123 surrounds the shank of the latch between one end of the bracket and a pin 124. By pushing the latch outwardly and engaging its head in the slot 120 the spring will be placed under compression and the bar 77 will be held in an elevated position or in such position as to retain the lugs 78 and 79 out of engagement with the rollers, thereby preventing opening of the valves. The bar is latched before the housing is lowered into the well. When it is desired to begin operations the bar is lifted so as to free the head of the latch, whereby the spring immediately withdraws the latch out of the path of said bar.

If a well began flowing under its own pressure it would be desirable to cut off the supply of gas from the surface and hold the oil valves 68 and 69 and the gas valves 47 and 48 open. This could be accomplished by locating the lugs 78 and 79 so that the upper end of the lug 78 would engage the roller 55' while the lower end of the lug 78 was still in engagement with the roller 55.

What I claim and desire to secure by Letters Patent is:

1. A well fluid lifting apparatus including, a pressure fluid inlet valve, a liquid inlet valve, said valves being adapted to be installed in a well, a conductor connected with said valves for receiving fluid and liquid therefrom, means for opening and closing said valves having a positive actuating element extending up the well for connection with surface operating means, and means operable from the surface for disconnecting the actuating element, whereby it may be removed from the well.
2. A well fluid lifting apparatus including, a pressure fluid inlet valve, a liquid inlet valve, said valves being adapted to be installed in a well to admit liquid and pressure fluid therefrom, a conductor connected with said valves for receiving fluid and liquid therefrom, movable means for operating said valves, and actuating means for said movable means extending from said movable means up the well to the surface for imparting motion from the surface to positively open and close said valves.
3. A well fluid lifting apparatus including, a pressure fluid inlet valve, a liquid inlet valve, said valves being adapted to be installed in a well to admit liquid and pressure fluid therefrom, a conductor connected with said valves for receiving fluid and liquid therefrom, movable means for operating said valves, actuating means for said movable means extending from said movable means up the well to the surface for imparting motion from the surface to positively open and close said valves, and means for releasing the actuating means from the movable means.
4. A well fluid lifting apparatus including, a pressure fluid inlet valve, a liquid inlet valve, said valves being adapted to be installed in a well to admit liquid and pressure fluid therefrom, a conductor connected with said valves for receiving fluid and liquid therefrom, a movable member for actuating said valves, and an elongate actuating member connected with the movable member and extending up the well to the surface.
5. A well fluid lifting apparatus including, a pressure fluid inlet valve, a liquid inlet valve, said valves being adapted to be installed in a well to admit liquid and pressure fluid therefrom, a conductor connected with said valves for receiving fluid and liquid therefrom, a movable member for actuating said valves, an elongate actuating member connected with the movable member and extending up the well to the surface, and means operable from the surface for disconnecting the actuating member from the movable member.
6. A well fluid lifting apparatus including, a pressure fluid inlet valve, a liquid inlet valve, said valves being adapted to be installed in a well to admit liquid and pressure fluid therefrom, a conductor connected with said valves for receiving fluid and liquid therefrom, a vertically sliding member for actuating said valves, and an elongate actuating member connected with the sliding member and extending up the well to the surface.
7. A well fluid lifting apparatus including, a pressure fluid inlet valve, a liquid inlet valve, said valves being adapted to be installed in a well to admit liquid and pressure fluid therefrom, a conductor connected with said valves for receiving fluid and liquid therefrom, a vertically sliding member for actuating said valves, and an elongate flexible actuating member connected with the sliding member and extending up the well to the surface.
8. A well fluid lifting apparatus including, a pressure fluid inlet valve, a liquid inlet valve, said valves being adapted to be installed in a well to admit liquid and pressure fluid therefrom, a conductor connected with said valves for receiving fluid and liquid therefrom, a vertically sliding member for actuating said valves, an elongate flexible actuating member connected with the sliding member and extending up the well to the surface.
9. A well fluid lifting apparatus including, a conductor extending up the well, an inlet valve for admitting fluid under pressure to the conductor, a second inlet valve for admitting liquid to said conductor, both of said valves being adapted to be installed in a well, means arranged for operating said valves to alternately admit liquid and fluid to said conductor to lift the liquid therein, and positive actuating means extending from the operating means to the surface of the well.
10. A well fluid lifting apparatus including, a conductor extending up the well, an inlet valve for admitting fluid under pressure to the conductor, a second inlet valve for admitting liquid to said conductor, both of said valves being adapted to be installed in a well, means arranged for operating said valves to alternately admit liquid and fluid to said conductor to lift the liquid therein, positive actuating means extending from the operating means to the surface of the well, and a weight for holding the actuating means taut and taking up the slack and stretch therein.
11. A well fluid lifting apparatus including, a conductor extending up the well, an inlet valve for admitting fluid under pressure to the conductor, a second inlet valve for admitting liquid to said conductor, both of said valves being adapted to be installed in a well, means arranged for operating said valves to alternately admit liquid and fluid to said conductor to lift the liquid therein, positive actuating means extending from the operating means to the surface of the well, and a weight arranged to operate the operating means when the actuating means is moved downwardly.
12. A well fluid lifting apparatus including, a conductor extending up the well, an inlet valve for admitting fluid pressure to the conductor, a second inlet valve for admitting liquid to said conductor, both of said valves being adapted to be installed in a well, means for operating said valves to admit liquid and fluid to said conductor to lift the liquid therein, an auxiliary fluid inlet valve, means for operating the auxiliary fluid inlet valve and the liquid inlet valve, and positive actuating means for operating said valve operating means extending up the well to the surface.
13. A well fluid lifting apparatus including, a pressure fluid inlet valve, a liquid inlet valve, said valves being adapted to be installed in a well to admit liquid and pressure fluid therefrom, a conductor connected with said valves for receiving fluid and liquid therefrom, a tripping device connected with the fluid inlet valve for operating the same, a second tripping device connected with the liquid inlet valve for operating the same, a vertically moving tripping bar having means for actuating said tripping devices, and actuating means extending from the tripping bar up the well to the surface.

14. A well fluid lifting apparatus including, a pressure fluid inlet valve, a liquid inlet valve, said valves being adapted to be installed in a well to admit liquid and pressure fluid therefrom, a conductor connected with said valves for receiving fluid and liquid therefrom, a tripping device connected with the fluid inlet valve for operating the same, a second tripping device connected with the liquid inlet valve for operating the same, a vertically moving tripping bar having means for actuating said tripping devices, a flexible actuating connection extending from the tripping bar up the well to the surface, and a weight for holding the flexible connection taut.
15. A well fluid lifting apparatus including, an elongate housing, a liquid inlet valve in the lower end of the housing, a fluid inlet valve in the housing having an inlet in the upper portion of said housing, said housing being adapted to be installed in a well to receive fluid and liquid through said valves, a conductor extending from said housing for conducting fluid and liquid therefrom, means movable in the housing for operating said valves, and actuating means extending from said movable means up the well to the surface for imparting motion from the surface to positively open and close said valves.
16. A well fluid lifting apparatus including, an elongate housing, a liquid inlet valve in the lower end of the housing, a fluid inlet valve in the housing having an inlet in the upper portion of said housing, said housing being adapted to be installed in a well to receive fluid and liquid through said valves, a conductor extending from said housing for conducting fluid and liquid
- therefrom, means arranged for operating said valves to alternately admit liquid and fluid to said housing to lift the liquid in the conductor, and positive actuating means extending from the operating means to the surface of the well.
17. A well fluid lifting apparatus including, an elongate housing adapted to be installed in a well and submerged in the liquid standing therein, a liquid inlet valve mounted in the lower end of the housing, a closure in the upper end of the housing having a passage therethrough for connection with the well tubing, a fluid inlet valve mounted in the housing, a fluid inlet conductor extending into the housing to said inlet valve, individual operating elements for said valves, a vertically moving device in said housing having means for actuating the valve operating means, and an elongate actuating member extending from the surface of the well down into the housing and connected with the said device for operating the latter from the surface of the well.
18. A well fluid lifting apparatus including, a pressure fluid inlet valve, a liquid inlet valve, said valves being adapted to be installed in a well to admit liquid and pressure fluid therefrom, a conductor connected with said valves for receiving fluid and liquid therefrom, movable means for operating said valves, actuating means for said movable means extending from said movable means up the well to the surface for imparting motion from the surface to positively open and close said valves, and a latch for holding the movable means against operation arranged to be released by the actuating means.
